US0D1108532S

(12) **United States Design Patent** (10) **Patent No.:** **US D1,108,532 S**
(45) **Date of Patent:** **** Jan. 6, 2026**

(54) **SELF-CHECKOUT STATION**

(71) Applicant: **Toshiba Global Commerce Solutions, Inc.**, Durham, NC (US)

(72) Inventors: **Brad M. Johnson**, Raleigh, NC (US); **William L. Dungan**, Cary, NC (US)

(73) Assignee: **Toshiba Global Commerce Solutions, Inc.**, Durham, NC (US)

(**) Term: **15 Years**

(21) Appl. No.: **29/907,304**

(22) Filed: **Jan. 5, 2024**

(51) LOC (15) Cl. **18-01**

(52) U.S. Cl.

USPC **D18/4.1**; D18/4.4; D14/307; D6/699

(57) **CLAIM**

The ornamental design for a self-checkout station as shown and described.

DESCRIPTION

FIG. 1 is a top-right-front perspective view of a self-checkout station showing the claimed design;

FIG. 2 is a top-left-front perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.

The broken lines in the Figures show portions of the self-checkout station that form no part of the claimed design.

1 Claim, 8 Drawing Sheets
